CLOTHESLINE TIGHTENER

Filed Oct. 14, 1927

INVENTOR.
Frank B. Simpson

BY
John J. Simpson
ATTORNEY'S

UNITED STATES PATENT OFFICE.

FRANK B. SIMPSON, OF POUGHKEEPSIE, NEW YORK.

CLOTHESLINE TIGHTENER.

Application filed October 14, 1927. Serial No. 226,055.

This invention relates to a device for tightening or winding up the slack in clothes lines, and particularly to that class of lines where two pulleys are employed, one of 5 which is attached to the house and the other to a pole in the yard, and the line is run through both pulleys and the ends secured to the tightener to form an endless line.

While there are some devices now in use 10 for this purpose they are either attached or form a part of one of the pulleys, or they are complicated, containing many parts, such as ratchets, pawls, etc., which become useless after being some time subjected to weather 15 conditions.

The object of the present invention is to provide a simple and effective device for this purpose that shall be easily installed, contain few parts and be very strong and durable, and capable of winding up a quantity 20 of line.

Another object of the invention is to provide a device of this kind that shall be open to prevent the catching of snow or other 25 matter to become clogged and rust the device.

With these and other objects in view my invention consists in certain novel construction and combination of parts as will herein-after be fully described and claimed and 30 illustrated in the accompanying drawings which form a part hereof and in which like figures of reference refer to corresponding parts in all of the views, and in which—

Figure 1 shows the device in use as applied 35 to a line mounted on two pulleys.

Figure 2 is a top plan view of the device, showing the two ends of line attached, but not wound up.

Figure 3 shows a side elevation of the 40 same.

Figure 4 shows an end view, illustrating the manner of locking the crank.

Figure 5 is a detail view of the eye in the shaft.

Referring to the drawings, the device 45 comprises a frame in the form of a rectangle and constructed of one piece of sheet metal or other suitable material, although I do not confine myself to this construction, as a casting may be employed and of a different 50 shape if desired.

As shown this piece of sheet metal is shaped with a curved end 10, the straight sides 11 and the short ends 12 overlapped and pierced with holes in registry with each other, and through which is placed a hollow rivet 13, which serves the double purpose of holding the ends 12 together and forming a 55 guide for the clothes line 14 to pass through.

The end 10 is also formed with a hole in line with the holes in the ends 12, and a similar tubular rivet 15; and to one side of the frame is attached also by the rivets 13 and 15, a curved handle 16, of like or suitable 60 material.

For winding up the clothes line, there is provided a combined shaft and hand crank which is formed with the shaft portion 17 rotatably mounted in holes formed in the sides 11; and a crank portion 18 without the frame 70 and bent at right angles thereto.

Said shaft portion 17 is also formed with an eye 19 within said frame, and in contact with the inner surface of one side thereof, to prevent the removal of said shaft, and 75 through this eye 19 is passed one end of the clothes line 14 and a knot 20 tied therein, while the other end of the line 14 after passing through the two pulleys 21 is passed through the tubular rivet 13 and knotted. 80

As the frame is held by the handle 16, and the shaft 17 rotated by the crank 18 the line will be wound up on said shaft, and to retain said shaft from rotation in the opposite direction and lock it, there is provided a 85 latch 22 having one end pivoted to the end 10 and the other end resting on the edge of the side 11 and hooked under the crank 18 as shown in Figure 4, and when it is desired to release the crank to let out the line, this latch is turned back from engagement with the crank, and it will thus be noted that as the crank is rotated forward to wind up on the line, that it will raise and pass the latch at every revolution, but can not turn back. 90

Having thus described my invention, what I claim as new and desire to secure by Letters Patent, is:

In a clothes line tightener of the class described, and in combination with a rectangular frame formed with aligned holes in the ends thereof, and aligned bearings in the sides 100

thereof, of a combined shaft and crank, comprising a straight portion mounted in said bearings, an eye formed therein within said frame and preventing the withdrawal of said shaft, said shaft being bent into the form of a crank without said frame, and a latch having one end pivoted to one end of

said frame, with its free end resting upon the opposite side of said frame, for the purpose of preventing the backward rotation of said crank. 10

In testimony whereof I affix my signature.

FRANK B. SIMPSON.
